UNITED STATES PATENT OFFICE

WILLIAM POOL, OF SPONDON, NEAR DERBY, ENGLAND, ASSIGNOR TO CELANESE CORPORATION OF AMERICA, A CORPORATION OF DELAWARE

LOOM HAVING A STATIONARY WEFT SUPPLY

Application filed September 9, 1931, Serial No. 561,839, and in Great Britain September 12, 1930.

This invention relates to looms having a stationary weft supply and in particular to that class of loom in which a measured loop of weft of a length sufficient for two picks is drawn from a weft supply, and the picks are inserted in turn into separate sheds.

In this class of loom weft is supplied from a stationary yarn package and is fed to a loop measuring device, the weft being secured by one of two trapping devices between which it is drawn into loop form by travelling means adapted to pass between the two trapping devices. The weft is seized by the second device when the required length of weft has been drawn, the travelling means then releasing itself from the loop of weft.

The weft is then ready for insertion into the shed, the first trapping device releasing its end of the loop so that the limb of the loop which has been attached to that device can be presented to a dummy shuttle or other weft inserter and carried into the shed. The remaining limb of the loop is afterwards severed from the weft supply near to the second trapping device, which retains its hold on the end of the weft connected to the supply, and is presented in turn to the inserting means generally after insertion of a pick of weft from the other side of the loom. The loop of weft is thus laid as a "hairpin" in the fabric, with its two limbs in separate sheds.

In order to maintain tension on the first pick during beat-up and to keep the second limb of the loop in proper position for presentation to the inserter, a loop retaining member is caused to enter the bight of the loop, so that after insertion of a limb of the loop the weft passes from the edge of the fabric and round the retaining member to the second trapping device.

It will readily be seen that for the first insertion a length of weft must be available for presentation to the weft inserter which exceeds the width of the fabric by the distance between the edge of the fabric and the retaining member, while for the second insertion the amount of the second pick is made

up of the length extending from the edge of the fabric to the second trapping device round the retaining member.

Though in order to keep the width of the loom to a minimum, the path of the travelling means is arranged as near to the edge of the fabric as possible, it is necessary in practice for there to be a considerable gap between the path of the travelling means and the edge of the fabric. This makes a considerable difference between the amount of weft which has to be available for the first insertion and the amount remaining between the retaining member and the second trapping device before the second insertion. This difference may be provided for during formation of the weft by allowing sufficient travel of the travelling means beyond the retaining member before release of the bight of the loop, but in view of the fact that the retaining member should be placed roughly in the line of the fell of the fabric so that on beat-up of the first pick the weft extends in practically a straight line from the far edge of the fabric through the fabric to the retaining member, and since release from the bight of the loop must take place only a very short distance in front of the fell of the fabric in order to avoid mechanism projecting beyond the front of the loom, the amount thus available is relatively small.

Moreover, when it is remembered that it is most advisable to arrange that the loom can weave fabrics of greatly differing width, and that the position of the retaining member at the side of the loom does not permit of adjustment with respect to the edge of the fabric, it will be seen that the amount of weft length adjustment which might be made available in the manner referred to above is inadequate for all widths of fabric. For example, if a fabric of considerably less width is to be woven, it will be seen that while the amount of weft available for insertion of the first pick has to be reduced by an amount corresponding to half the reduction of the width of the fabric, a greatly increased distance has to be covered between the edge of the fabric and the retaining member after the first pick, and the amount available be-

5 between the retaining member and the second trapping device for the second pick has to be reduced still more because of the increased amount between the edge of the fabric and the retaining member going to make up the second pick. It becomes impossible to provide for these differing conditions by an adjustment between the position of the release of the bight of the loop and the retaining member; yet at the same time it is undesirable to effect the adjustment by individual movement of the trapping devices towards and away from the point of release of the loop, in view of the fact that for some widths 10 of fabric the two devices would thus require to be so far apart that insertion of the weft during loop formation into the trapping device which for the time being is open becomes uncertain. For this reason it is important to keep the trapping devices, whatever the width of fabric being woven, as close together as possible, preferably in fact, so close as only to afford just sufficient room 15 for the passage between them of the travelling means.

20 The principal object of the present invention is to enable the correct loop length to be drawn and correct amounts of weft to be available for the first and second picks, while 25 enabling the weft to be engaged with certainty by the trapping devices. A further object of the invention is to enable correct measuring of the weft to be effected without 30 the necessity for individual adjustment of the trapping devices. A still further object of the invention is to enable correction of the 35 loop length to be effected by the act of forming the weft loop itself.

40 According to the invention the weft is brought by the travelling means into engagement with means which form a subsidiary loop within the main loop during the formation of the main loop by the travelling means, the extra length thus added to the main loop 45 being available for engagement by the weft inserter on insertion of the first pick.

50 Thus, the travelling loop-forming means may comprise two pegs or rollers spaced apart so as to bring the short length of weft 55 extending between them into engagement with a further peg or roller, the continued movement of the travelling pegs or rollers causing the bight end of the weft-loop to be doubled back into a subsidiary loop within the main loop. The further peg or roller is 60 preferably fixed, but may be adjusted relatively to the travelling pegs or rollers to produce a subsidiary loop whose length corresponds with the distance between the edge 65 of the fabric and the retaining member for all widths of fabric. Compensation for this difference being thus provided, variation in the length of the main weft loop can be effected by moving the trapping devices together without altering their distance apart.

70 The loop forming means may be of any convenient form, it being preferred to use two travelling devices for engaging the weft in turn, so that while a loop is being formed by the one device, the second device is moving into position in readiness for forming a second loop. Thus, for example, an endless band or chain may be arranged to traverse a path in proximity to which the weft loops are to be formed so that pegs, rollers, or the like on the band or chain engage the weft between the two trapping devices. Similarly 75 one or more oscillating or reciprocating hooked arms or rods may be used for the same purpose.

80 Means may be provided to retain tension in the weft thread during beat-up, after one limb of the loop has been inserted, the means for this purpose being further adapted to be removed when the second limb is being inserted and to be displaced in case of accidental contact with the travelling device.

85 The retaining member is preferably locked in position to maintain and control the tension on the first pick of weft during beat-up, and may also be arranged to move against spring action, as described in U. S. application S. No. 484,785 dated 27th September, 1930, to avoid excessive tension on the first pick by movement of the trapping device holding the end of the second pick, if movable trapping devices are used.

90 A weft loop having been formed at one side of the loom, it is presented one limb at 95 a time to inserting means which may be of the dummy shuttle type; or a rigid or flexible inserting member which carries the limb part way through the shed and transfers it to a withdrawing member which carries it through the remainder of the shed; or a member which carries the limb through the whole of the shed.

100 Weft loop formation may take place at each side of the loom, devices being provided to present the limbs of the loops in 105 any desired order to the inserting means.

110 The invention will now be described in greater detail with reference to the accompanying drawings. It is to be understood, however, that the following description is given by way of example only and is in no 115 way limitative.

115 In the drawings:

120 Fig. 1 is a side elevation of the loop-length adjusting means according to the invention;

125 Fig. 2 is an end elevation of the mechanism shown in Fig. 1, looking in the direction 2-2;

130 Figs. 3, 4 and 5 show three different positions of the mechanism shown in Fig. 1, Fig. 5 showing also an operating cam mechanism;

135 Fig. 6 is another view of the cam mechanism of Fig. 5; and

Figs. 7 to 10 are diagrammatic views illustrating the manner in which weaving takes place.

Weft thread supplied from a stationary bobbin is led to one of a pair of trapping devices mounted on a disc which is rotated to cause the weft engaged by one trapping device to be engaged by the second trapping device as described in U. S. application S. No. 10 484,785 dated 27th September, 1930, and as illustrated diagrammatically in Figs. 7 to 10 of the accompanying drawings. The loop-forming means comprises a pair of small pegs or rollers 11 which project from an 15 endless chain 12 which carries the pegs 11 towards the front of the loom, thus drawing a loop of weft 13 from a stationary bobbin (not shown). The two pegs 11 which may be of capstan shape, are mounted on a trans- 20 verse plate 14 attached to a small bracket 15 carried by the endless chain, the two pegs being spaced a little distance apart.

The weft loop 13 thus formed passes between the pegs 11, and at some distance before the pegs are released from the loop, the portion of the loop between the pegs engages a projection 16, so that the continued movement of the pegs 11 causes the projection 16 to draw a subsidiary loop which extends 30 backwards from the pegs 11.

The projection 16 is attached by means of a wing nut 17 to a bracket 18 mounted in front of the sprocket 19 round which the chain 12 turns to release the pegs 11 from 35 the weft loop 13. The bracket 18 is slotted in the direction of the chain run and the wing nut 17 enables the position of the projection 16 to be adjusted in accordance with the length of subsidiary loop required. The 40 pegs 11 extend to such a height above the chain 12 as to reach the axis 20 of the sprocket 19 as the chain 12 runs round the sprocket 19, so that the loop 13 is drawn out as far as the axis 20 and then released from the 45 pegs.

On release of the loop one limb is presented to a dummy shuttle or the like and inserted in the shed, the bight of the loop being drawn back from the point of release, 50 a guard 23, whose front edge may constitute the projection 16, preventing fouling of the loop on the projection 16 as the weft is drawn past the projection 16 by the dummy shuttle carrying the weft into the shed. In this 55 way, the weft engages a retaining member 24 which has been inserted in the loop 13, by means to be described later, just after the passage of the rollers 11. A guard 12 prevents the weft from fouling the chain 12 as 60 it is being pulled into the shed.

The retaining member 24 is inserted into the loop by means of a toggle mechanism consisting of links 25, 26, a rod 27 and a lever 28. A toggle mechanism is operated by 65 means of a rod 29 and a bell crank 30 which

is held by means of a spring 31, against the action of a cam which operates the rod 29. The links 25, 26 are pivoted to a collar 32 sliding in the rod 27 and retained in position thereon by a spring 33, while the other end of the link 26 is pivoted to a rod 34, sliding in a lug 35 against the action of a spring 36. The other end of the link 25 is attached to the lever 28, while the top of the rod 27 is connected to a lever 30, actuated through a lever 130 from the rod 29. The means for operating the rod 29 are shown in Fig. 5 to be referred to hereafter.

In Fig. 1 the member 24 is shown locked in position by the links 25, 26 having been brought into alignment with each other. In order to maintain and control the tension on the weft, the toggles 25, 26 are released, thus allowing the finger 24 to move against the action of the spring 33. Further, as described in U. S. application S. No. 484,785 dated 27th September, 1930, in order to avoid excessive tensioning of the weft by movement of a trapping device which is moving while still holding the second limb of the loop 13, the rod 29 is permitted to move to the right under the action of the spring 31 to allow the finger 24 to move to the position shown in Fig. 4, the spring 33 continuing to maintain the desired tension on the weft. The compression of the spring 33 is adjusted by means of the lock nuts 33'.

Immediately before the shuttle engages the second limb of the loop 13, the retaining member 24 is whipped out of the loop by a movement of the rod 29 to the right, as shown in Fig. 5.

The means for operating the retaining member 24 is shown in Figs. 5 and 6. The rod 29 is pivotally connected to a lever 38 pivoted at 39 and connected by a rod 40 to one limb of a bell-crank lever 41, the other end of the bell-crank lever carrying a bowl 42 and a nib 43. The bowl 42 engages with a cam 44 rotating on a shaft 44', while the nib 43 is engaged by a supplementary cam plate 45, attached to one side of the cam 44. The weft retaining member 24 is brought into the position shown in Fig. 1 by the engagement of a quick rise 46 on the cam 44 with the bowl 42. Following the quick rise 46 is a gradual drop to the point 47, at which point the nib 43 by engaging with the plate 45 has lifted the bowl 42 from the cam surface, bringing the weft retaining member 24 to the position shown in Fig. 4 under the action of the spring 31. At the point 47 and nib 43 drops suddenly over the end of the plate 45, causing the weft retaining member 24 to be whipped out of the loop just before picking occurs, this position being shown in Fig. 5. After this sudden drop, the bowl 42 returns to the cam surface 44. Should for any reason the finger 24 be in the path of the pegs 11, it can be lifted

by the pegs without damage to either part, the rod 34 connected to the toggles 25, 26 being capable of movement against the action of the spring 36 to permit this movement of the finger 24. The toggle mechanism and the subsidiary loop forming mechanism is carried in a frame 48 which is attached to the end frame 49 and cross member 50 of the loom, the position of the mechanism on the loom being indicated by the illustration in Fig. 1 of the sley 37, which is shown in its forward or beat-up position and not in a position corresponding to the position of the parts of the loop forming mechanism.

Figs. 7 to 10 show the sequence of operations of drawing the loops and inserting them as picks of weft into the fabrics on a loom provided with weft compensating means according to the invention. Though in these figures, moving trapping and cutting devices are shown of the type described in U. S. application S. No. 484,785 dated 27th September, 1930, it will readily be understood that any other form of device enabling the presentation of weft to loop-forming means to be effected may be employed. In each figure, loop formation at both sides of the loom is shown, one side being approximately one pick out of phase with the other.

The associated trapping and cutting devices 52, 53 and 52', 53' are carried respectively on discs 51, 51' which rotate to cause the weft to extend between the trapping devices on each disc for the engagement of the weft by loop forming devices.

On the left-hand side of Fig. 7 a weft loop comprising limbs 54, 56 has been drawn out by the pegs 11 between trapping and cutting devices 52, 53, the projection 16 having been engaged by the weft between the pegs 11 to produce a subsidiary loop 55.

On the left-hand side of Fig. 8 the limb 54 is shown released from the trapping device 52 in readiness for insertion into the shed, the retaining finger 24 having been inserted into the loop. The right-hand side of Fig. 7 shows loop formation which proceeds to the extent shown on the left-hand side of Fig. 8. On the right-hand side of Fig. 8 the limb 54' is shown inserted into the fabric and drawn up against the retaining member 24'.

On the left-hand side of Fig. 9 the limb 54 is picked into the fabric to follow the pick 54', and the left-hand side of Fig. 10 shows the limb 56' about to be released from the retaining member 24 for insertion into the shed, it being clear that the length of the limb 54, together with the length of weft 60 in the subsidiary loop 55, enables the weft to extend from the finger 24 to the other side of the fabric.

Following the pick 54 from the left-hand side the limb 56' of the loop at the right-hand side is picked into the fabric, as shown in

Fig. 10. The limb 56 follows from the left-hand side the pick 56', the limb 56 carrying with it into the shed the length of weft extending between the pick 54 and the finger 24.

During the insertion of picks in the order above described, further weft loops are being produced at the two sides of the loom. The right-hand side of Fig. 7 shows weft 61' engaged by the trapping device 53 and extending back to the supply package, not shown, about to be engaged by the trapping device 52'. At the left-hand side of that figure, the trapping device 52 is shown moving towards the weft 61 in readiness for the formation of a loop at that side of the loom. On the right-hand side of Fig. 8 a further pair of travelling pegs 11" is shown as having passed between the trapping devices 52', 53' to commence the formation of a further weft loop. The right-hand side of Fig. 9 shows this new weft loop 57' drawn to about two-thirds its full length, and the right-hand side of Fig. 10 shows it at almost full length with the projection 16' drawing a subsidiary loop 60' as before. The limbs of this new weft loop 57' are inserted into the fabric in the same manner and order as the limbs 54', 56' of the preceding loop on that side of the loom. In a similar manner a further loop 57 is drawn on the left-hand side of the loom by pegs 110 which follow the pegs 11 in the loop forming operation.

What I claim and desire to secure by Letters Patent is:—

1. Weft-measuring apparatus for looms having a stationary weft supply, said apparatus comprising means for drawing a measured loop of weft, and means into engagement with which the weft is brought by the loop-forming means so as to form a subsidiary loop within the main loop during the formation of the main loop.

2. Apparatus according to claim 1, comprising a pair of travelling pegs adapted to engage the weft thread and to draw it out into a measured loop, and a further peg adapted to engage the length of weft between said pair of pegs, so that the continued movement of the pair of pegs past the further peg draws the weft into a subsidiary loop within the main loop.

3. Apparatus according to claim 1 comprising a pair of travelling pegs having the form of freely-mounted rollers and adapted to move into engagement with the weft thread and to draw it out into a measured loop, and a further peg adapted to engage the length of weft between said pair of pegs, so that the continued movement of the pair of pegs past the further peg draws the weft into a subsidiary loop within the main loop.

4. Weft measuring apparatus for looms having a stationary weft supply, said apparatus comprising means for drawing a measured loop of weft, means into engage-

ment with which the weft is brought by the loop-forming means so as to form a subsidiary loop within the main loop during the formation of the main loop, and means for adjusting the length of the subsidiary loop drawn within the main loop.

5. Apparatus according to claim 4 comprising a pair of travelling pegs adapted to move into engagement with the weft thread and to draw it out into a measured loop, a

further peg adapted to engage the length of weft between said pair of pegs, so that the continued movement of the pair of pegs past the further peg draws the weft into a subsidiary loop within the main loop, and means for adjusting the position of the further peg so as to enable the length of the subsidiary loop drawn within the main loop to be adjusted.
